E. M. TUCKER

FLASHING STRUCTURE

Filed Jan. 17, 1927

INVENTOR
EDGAR M. TUCKER
BY *Charles S. Evans*
HIS ATTORNEY.

UNITED STATES PATENT OFFICE.

EDGAR M. TUCKER, OF SOUTH PASADENA, CALIFORNIA, ASSIGNOR TO THE PARAFFINE COMPANIES, INC., OF SAN FRANCISCO, CALIFORNIA, A CORPORATION OF DELAWARE.

FLASHING STRUCTURE.

Application filed January 17, 1927. Serial No. 161,492.

My invention relates to flashing structures, and particularly to a double seal counter-flashing.

An object of my invention is to provide a 5 flashing structure for use on a roof where no reglet or other provision has been made for the insertion of the usual counterflashing.

A further object of the invention is to provide a double waterproof seal for the roofing 10 edge.

My invention possesses other objects and valuable features, some of which, with the foregoing, will be set forth in the following description of the preferred form of my 15 invention which is illustrated in the drawing accompanying and forming part of the specification. It is to be understood that I do not limit myself to the showing made by the said drawing and description, as I may 20 adopt variations of the preferred form within the scope of my invention as set forth in the claims.

Referring to the drawing:

The figure is a perspective view of a piece 25 of my counterflashing applied to the protection of the upturned ends of sheets of flexible roofing. One of the fastening means is shown in section.

Broadly, the flashing structure of my invention comprises a metal strip, preferably 30 of galvanized iron or other rust resisting material, and having therein a succession of apertures in a line parallel to the upper edge of the strip, to receive nails or other suitable means of attaching the strip to its 35 substructure. An outwardly extending corrugation runs longitudinally of the strip between the line of apertures and the upper edge of the strip; and the upper edge is also 40 preferably turned outwardly to form a lip. Thus two longitudinally disposed recesses are provided between the strip and the wall for the reception of a plastic sealing material. The lower edge of the strip is adapted 45 to overlie the upturned edge of the roofing, which may be the flexible roof covering of common usage, and thus forms an apron therefor. My invention is used to provide a double waterproof seal for the upturned 50 edge of the roof covering, wherever any object, such as a chimney or parapet wall, projects from the flat surface of the roof.

In its present embodiment, my counter-flashing is shown in conjunction with a para-

pet wall 6, projecting above a roof 7. Overlying the roof are one or more sheets of flexible covering 9, having its edges 11 turned up against the parapet wall 6.

My counterflashing comprises a strip 12 of sheet material resistant to deterioration by the weather, such for example as galvanized iron. This strip is adapted to be secured to the wall so that its lower edge 13 overlies and supports the upturned edge 11 of the roof covering, providing an apron 65 therefor. Means are provided for attaching the strip to the wall. Punched in a line preferably parallel to the edges of the strip are a succession of apertures, each adapted to receive a nail 16, which is driven thru the 70 aperture into an expansion bushing 17 seated in an associated aperture 18 drilled in the parapet wall. The bushing is split longitudinally, and the parts held together by a band 19 of relatively soft metal, such 75 as lead. The bore of the bushing is less than the diameter of the nail; therefore, when the nail is driven home, the parts of the bushing are forced apart, causing the band 19 to expand to fill the hole 18, thus clamping the 80 nail tightly in place.

A longitudinally disposed, outwardly extending corrugation 21 between the row of apertures and the upper edge 22 of the strip and having its upper ridge adapted to 85 lie against the wall, provides a recess between the strip and the wall for the reception of a waterproof plastic sealing material 23. This recess ordinarily is filled before the strip is fastened in place; but it can easily 90 be filled afterwards if desired. This latter operation is facilitated by having the upper edge 22 bent outwardly in a lip to form a second recess open at the top. Any suitable tool can be inserted back of this lip, and 95 the parts sprung away from the wall far enough to permit the plastic material to be forced into the lower recess. Not only can the first filling of the recesses be easily accomplished in this way, but the supply of 100 plastic material in the recesses can be replenished in a similar manner at any time. Because the strip is possessed of a certain degree of resilience, and because it is supported at a point below the corrugation, the 105 upper edge may be sprung away from the wall without permanent deformation of the strip.

Having the upper edge bent outwardly in this manner to provide a second recess open at the top, furnishes a first line of defense against leakage, and the roofing edge is 5 doubly sealed. Furthermore the sealing material in the larger or lower recess is protected from the weather and therefore remains pliable and adapted to fill automatically any opening which may appear.

10 Not only does my counterflashing permit the secure double sealing of the roofing edge where no reglet has been let into the parapet wall to receive it, but the counterflashing lends itself to application in positions 15 not possible with other structures because of their more complex construction. Furthermore, it is cheaply rolled from a single strip of metal, and because of the ease of cutting the strip, it is readily applied in 20 corners and around chimneys and other irregular places.

I claim:

1. A counterflashing comprising a strip of sheet metal adapted for fastening to a wall 25 over the exposed ends of a covering, and having adjacent its upper edge a longitudinally disposed outwardly extending corrugation to provide a recess between the strip and the wall, and having the upper

edge turned outwardly to provide a second 30 recess open at the top, said recesses being adapted to be filled with a plastic sealing material.

2. A counterflashing comprising a strip 35 of sheet metal having a succession of apertures therein for the reception of means to fasten the strip on a wall, and a longitudinally disposed outwardly extending corrugation to provide a recess between the strip and the wall disposed between said 40 apertures and the upper edge of the strip, said strip having its upper edge turned outwardly to provide a second recess open at the top, and said recesses being adapted to be filled with a plastic sealing material. 45

3. A counter-flashing comprising a strip of sheet metal adapted for fastening to a wall over the exposed ends of a covering, and having adjacent its upper edge a longitudinally disposed outwardly extending corrugation having its upper ridge adapted to lie against the wall to provide a recess between the strip and the wall for the reception of a plastic sealing material.

In testimony whereof, I have hereunto 55 set my hand.

EDGAR M. TUCKER.
